UNITED STATES PATENT OFFICE.

ARNOLD H. HOTTINGER, OF CHICAGO, ILLINOIS.

SPRAYING DEVICE.

Application filed April 3, 1925. Serial No. 20,322.

The invention relates to improvements in pneumatic spraying devices, and particularly in devices adapted to spray paint.

The primary object of the invention is to

5 provide a novel spraying device which is adapted to apply paints of different colors simultaneously to a surface, to obtain a mottled color effect such as is frequently desired on ceramic tile and other articles.

10 A more specific object is to provide a novel paint spraying device having means for projecting a plurality of independent jets of paint upon the surface to be painted.

15 Another object is to provide a novel spraying device of the above character which is simple and inexpensive in construction, and which is adapted to be applied to a wide variety of uses.

20 Ancillary objects and advantages will become apparent as the description proceeds.

Referring to the accompanying drawings,

Figure 1 is a plan view of a spraying device embodying the features of my invention.

25 Fig. 2 is a sectional view thereof taken along line 2—2 of Fig. 1.

Fig. 3 is a front view thereof.

Fig. 4 is a rear end view thereof.

Fig. 5 is a fragmentary sectional view of the paint cut-off device.

30 While the invention is susceptible of various modifications and alternative constructions, I have shown in the drawings and will herein describe in detail the preferred embodiment, but it is to be understood that I do not thereby intend to limit the invention to the particular form disclosed, but aim in the appended claims to cover all modifications and alternative constructions falling within the spirit and scope of the invention.

40 Referring to the exemplary embodiment of the invention illustrated in the drawings, the spraying device comprises a flat base plate 10 which is substantially rectangular in shape, and on the front end of which a spray head 11 is mounted.

45 The spray head consists of a casing 12 which preferably is rectangular and box shaped in construction, and which extends across and is rigidly secured to the base plate 10 by screws 13. The interior of the casing constitutes a large air chamber adapted to receive compressed air from a fitting 14 opening through the base plate 10.

50 Formed in the front wall of the casing 12 and adapted to discharge air in small streams from the air chamber are a plurality of restricted air ports or orifices 15. These ports

are grouped in a plurality of sets, three in the present instance and in each set are arranged at equal distances about a central opening 16.

Extending through the casing 12 are a plurality of paint nozzles 17, one for each set of ports 15. Each nozzle is formed with a longitudinal passage, and is provided on its rear end with a hose attaching nipple 18 and with an enlargement 19 threaded into the rear wall of the casing 12. The front end of each nozzle 17 is reduced in size, extends tightly through one of the openings 16 located centrally of the ports 15 of each set, and is formed with a restricted jet passage 20.

A vertical bracket in the form of a plate 21 is rigidly secured to the rear end of the base plate 10, and is formed with a centrally depending lug 22 having an aperture 23. Extending through the aperture 23 in which it is clamped, and beneath the base plate 10 to the fitting 14 into which it is threaded is a pipe 24 which is adapted to receive a pressure fluid such as compressed air from any suitable source (not shown).

Three paint conduits 25 are rigidly mounted in holes 26 in the bracket 21 above the base plate 10, and are provided at their front and rear ends with hose attaching nipples 27 and 28 respectively. The front nipples 27 are connected by flexible hose 29 to the nipples 18 on the nozzle 17, and the rear nipples 28 are connected to supply hose 30 adapted to receive paints of the same or different colors from any suitable sources (not shown).

Mounted on the base plate 10 between the head 11 and the bracket 21 is a cut-off device for the hose 29. This device comprises two vertical standards 31 secured to opposite sides of the base plate 10 by screws 32. A pair of rotatable heads 33 are journaled in the standards 31, and are eccentrically connected by a clamping bar 34 overlying the hose 29. One of the heads 33 is provided with a handle 35 for revolving the bar 34 to clamp the hose 29 against the top plate 10 as shown in Fig. 5 or to release them as shown in Fig. 2.

In operation, compressed air is admitted to the casing 12 from the pipe 24, and is forcibly ejected from the ports 15 in small streams, thereby creating a substantial vacuum at each jet passage 20, and causing paint to be discharged therefrom when the hose 29 are open. Preferably paints of different colors are supplied to the nozzles 17 to obtain a mottled

color effect on the surface being painted. The supply of paint to the nozzle 17 can be cut off when desired by revolving the clamping bar 34 downwardly against the hose 29 to 5 collapse the latter against the base plate 10.

It is frequently desirable to spray different amounts of materials through the different nozzles 17. Thus where dark and light paints are used, less dark paint may be required 10 than light paint. The relative amount of the differently colored paints can be varied by substituting nozzles 17 having different sized bores and passages 20.

It will be evident that I have provided 15 an advantageous pneumatic spraying device which is provided with means for projecting a plurality of independent jets of paint, and which is therefore adapted to simultaneously spray paints of different colors upon a single surface. The device is simple and inexpensive in construction, and will not easily 20 clog or get out of order. It is well adapted for applying paint to ceramic tile where a mottled color appearance is often desired, 25 but it is contemplated that other uses may occur to those skilled in the art.

I claim as my invention:

1. A spraying device having, in combination, a flat base plate, a closed hollow casing 30 mounted on one end of said plate, a plurality of paint nozzles extending through said casing, each nozzle being threaded into the rear wall of said casing and having a restricted passage extending through the front 35 wall of said casing, said casing being formed in its front wall with means for discharging pressure fluid about said nozzles, a bracket secured to the other end of said plate and extending on opposite sides thereof, a plurality 40 of paint conduits rigidly mounted on said bracket at one side of said plate, a plurality of flexible conduits connecting said first mentioned conduits to said nozzles, and lying closely along said one side of said plate, means 45 for pressing said flexible conduits against

said plate to cut off the supply of paint to said nozzles, and a pressure fluid supply line opening through said plate into said casing and extending through said end bracket at the other side of said plate.

50

2. A spraying device having, in combination, a base plate, a closed hollow casing mounted on one end of said plate, a plurality of paint nozzles extending through said casing, said casing having a plurality of pressure fluid discharge openings arranged about 55 said nozzles, a bracket secured to the other end of said plate and extending on opposite sides thereof, a plurality of paint conduits rigidly mounted on said bracket at one side 60 of said plate, a plurality of flexible conduits connecting said first conduits to said nozzles and lying closely along said one side of said plate, means for pressing said flexible conduits against said plate to cut off 65 the supply of paint to said nozzles, and a pressure fluid supply line opening through said plate into said casing and extending through said end bracket at the other side 70 of said plate.

70

3. A spraying device having, in combination, an elongated base, a closed hollow casing mounted on one end of said base, a plurality of paint nozzles extending through said casing, said casing being formed with pressure fluid discharge openings about the discharge ends of said nozzles, a bracket secured to and extending across the other end of said plate, a plurality of paint conduits supported by one end of said bracket and 75 connected to said nozzles, and a pressure fluid line opening through said plate into said casing and supported by the other end of said bracket, said conduits and said line extending respectively along opposite sides of said 80 base.

75

In testimony whereof, I have hereunto affixed my signature.

ARNOLD H. HOTTINGER.
